UNITED STATES PATENT OFFICE.

DAVID M. MONROE, OF BALTIMORE, MARYLAND.

CAN-SOLDERING MACHINE.

SPECIFICATION forming part of Letters Patent No. 295,662, dated March 25, 1884.

Application filed January 15, 1884. (No model.)

To all whom it may concern:

Be it known that I, DAVID M. MONROE, a citizen of the United States, residing at Baltimore, in the county of Baltimore and State of Maryland, have invented certain new and useful Improvements in Can-Soldering Machines, of which the following is a specification, reference being had therein to the accompanying drawings.

10 My invention relates to improvements in can-soldering machines in which floats or end seams of round cans are soldered; and the objects of my improvements are, first, to either solder one or both the end seams at the same time; second, to either solder the can from the inside or outside, as may be desired; third, to cap or solder in the head of the can when filled with the goods; fourth, to provide means that will protect the side seam from being unsoldered when the heads are being soldered in; fifth, to support the mechanism on a central vertical shaft and from a suspended hanger. I attain these objects by the following mechanism, illustrated in the accompanying drawings, in which—

Figure 1 is a side view of the entire machine, part of which is in section; Fig. 2, a top view of the hanger and gear-wheels; Figs. 3 to 8, enlarged detail views of the mechanism that 30 imparts the intermittent motion to the rotary table; Figs. 9 and 10, details of the arm and segment-shaped piece that raise the can-clamping disks; Fig. 11, a top view of the upper plate of the rotary table; Figs. 12 to 20, detail views of can-holders; Fig. 21, side view of the machine when adjusted for capping the 35 filled cans; Figs. 22 and 23, detail views of cap-holding device, and Figs. 24 and 25 views of the cans.

40 Similar letters refer to similar parts throughout the different views.

The hanger A is suspended from above and provided with a yoke, through which the line-shaft B passes. On the latter is a pinion, a, clutched thereto by means of the sliding clutch b, provided with the lever b', by which the 45 machine is operated.

Through the perpendicular sleeve A' of the hanger A passes the vertical shaft C, the lower 50 end resting in the bearing f on the floor.

To the shaft C are attached the gear-wheel a',

which engages with the pinion a on the line-shaft B; the crank c, which vibrates the pendulum D; the external master gear-wheel, E, which rotates the can-holder d when in an inclined position; the internal master gear-wheel, F, which rotates the can-holder d when perpendicular; the cam e, which operates the solder-valve mechanism, and the rotary table G is supported and rotates freely thereon.

The table G consists of an upper and lower plate, g and g', connected rigidly together by means of the sleeve h. Attached to the periphery of the lower plate, g', are yokes i, in which the hubs i' are swiveled, and which are held or adjusted to the desired angle to engage the pinion k with either of the master-wheels E or F by means of the segment-shaped slot l on one arm of the yoke i, and a clamping-screw, f', which passes through the slot l and 70 into the hub i'. In the hub i' runs the spindle i'', to which is attached the can-holder d and the pinion k. The upper plate, g, is provided with an upward cylindrical projection, g'', in which are notches g''', ratchet-teeth u, 75 and arms m, projecting therefrom, which have upper and lower bearings, m' and m'', through which the spindle i'' passes.

To the spindle i'' is attached a clamping plate or disk, n, which holds the can H firmly 80 in the holder d by means of the spring n', which bears down on a flanged collar, n'', attached to the spindle i'' by means of a set-screw, n'', which allows the collar n'' to be adjusted to suit the heights of the different cans. 85 The spindle i'' and its attachment are lifted by the flanges n''' of the collar n'', which comes in contact with the segment-shaped piece o on the outer end of the arm o' as the table G rotates, the latter stopping with the can-holder 90 d opposite the center of the arm o', thereby holding the clamp or disk n up, allowing the operator to conveniently place or remove the cans. The intermittent movement is imparted to the table G by means of the crank e on the shaft C, provided with a roller, c', which comes in contact with the adjustable lugs or projections p and p' on the pendulum D, alternately. The pendulum D is pivoted to the downward-projecting rod q at one end, and 95 provided at the opposite end with the hollow boss r, containing therein a spring, and the pin

r', which engages with the ratchet-teeth *u* on the plate *g*. As the crank *c* rotates, the roller *c'* comes in contact with the lug *p*, thereby moving the pendulum *D* to one side, which then 5 remains stationary until the crank *c* makes part of its circuit, or until the roller *c'* comes in contact with the lug *p'*, which will move the pendulum *D* in the opposite direction to which it was first moved. The pin *r* in the 10 meantime engaging with a ratchet-tooth, *u*, on the plate *g*, the table *G* is rotated one-twelfth of its circumference, and then remains stationary until the roller *c'* again comes in contact with the lug *p'*. By the aforesaid mechanism 15 the table *G* is rapidly moved after the can is soldered, thereby freeing the can from the heat quickly, at the same time starting and stopping the table gradually. The table *G* is held rigid while the cans are being soldered, 20 placed, or removed by the pin *t'* in the sleeve *t*, engaging in the notches *g*³ on the plate *g*, and relieved therefrom by the lever *m'*, connected to the pin *t'* at one end, and at the opposite end pivoted to the rod *q*, the lever being 25 lifted by the upward-projecting incline *s* on the crank *c*, coming in contact with the downward-projecting incline *s'* on the lever *m'* at each rotation of the shaft *C*.

To the downward-projecting rod *q* at the 30 lower end is attached a projecting arm, *q'*, provided with a brake-shoe, *q*², which bears down on the cylindrical projection *g*² on the plate *g*, which prevents the table *G* from jumping forward when in motion, the whole being suspended 35 from the cross-arm *A*², which is attached to the hanger *A* by means of the set-screws *e' e'*.

The can-holders consist of cylindrical rings *d*, arms *d'*, and notched plates *d*². The plates 40 *d*² are placed on the arms *d'*, and are held to their places by the notches *l*, fitting over the upward projections *d*³ of arms *d'*, to prevent the scorching or discoloring of the can ends and the cap-crease. The outer ends of the arms *d'* 45 have upward projections *d*⁴, to which is attached the ring *d*, allowing the end of the can which rests on the arms *d'* to project below the ring *d* sufficient only to melt the solder therein, thereby protecting the upper part of 50 the can from the heat and effectually preventing the melting or unsoldering of the side seam. The holders *d* are changed to suit the different-sized cans by means of auxiliary rings *k'*, the inner diameter of the same suit- 55 ing the size of the cans to be soldered, while the outer diameter neatly fits in the ring *d*. The projecting shoulder *k*² on ring *k'* prevents the same from entering the ring *d* too far. To each set of auxiliary rings are corresponding 60 bottom plates, *d*². By this convenient arrangement any sized can smaller than the cylindrical ring *d* can be soldered, and in case of larger cans special holders are provided.

The arm *I* is attached to the cross-arm *A*² 65 by the rod *q*, provided with a clamping-nut, *q*⁴, and has an inward and outward adjust-

ment by means of a vertical slot, *o*³, through which the rod *q* passes. To the downward projection of the arm *I* is attached a receptacle, *L*, containing molten solder, which is 70 ejected on the ends of the cans by means of a valve formed by the rod *1*, (see Fig. 21,) which has a cone-shaped end resting in a counter-cone in the nipple *2*, which forms the seat of the valve, and is operated by means of 75 the bell-crank *3*, reciprocating rod *4*, cam *e*, and draw-spring *6*.

The machine is operated by one boy, who stands opposite the disk-lifting arm *o'*, placing and removing the cans, which are soldered in the following manner: When soldering both ends of the can without removing the same from the machine, the can is constructed as shown in Fig. 24, one end having the flange projecting over the can-body, and 85 the other end placed inside the same. Before or while placing the cans on the machine, a segment of wire-solder is placed in the can on the end which has the flange projecting over the can-body, the same end being placed in 90 the ring *d*. As the cans are carried around by the table *G*, they come in contact with the flame from the hydrocarbon-burners *R*, (which are placed opposite to where the can-holders stop, the number of burners depending on 95 the size of the cans and the speed at which the machine is run—ordinarily about four,) which fuses the solder placed in the can, and which is distributed around the seam by the rotation 100 of the same. The opposite end of the can having the end placed inside the body, (see Fig. 24,) forms a V-shaped groove, in which the molten solder is ejected from the receptacle *L* by means of the cam *e* and the intervening mechanism, the heat being applied to the cans 105 from burners placed as those above stated before and while the molten solder is ejected thereon.

Either of the aforesaid methods may be used independent of the other, one end of the 110 can being soldered in at a time, the molten-solder device being used if both end seams of the cans are to be soldered from the outside, the cans being constructed with both ends placed inside. (See Fig. 26.) To solder both ends 115 from the inside, the arm *I* and its attachments are dispensed with or removed, the can being soldered by the former method, as above stated, when using the segment of wire-solder, the can being constructed as shown in 120 Fig. 25.

When capping or soldering in the heads of filled cans, the machine is adjusted as shown in Fig. 21, with the can-holder *d* placed perpendicular, and the arms *m* on plate *g* removed and substituted by the arms *y* provided with the hollow hubs *y'*, springs *x'*, and pin *x*, which holds the head or cap down in its place, the pin *x* having a cone-shaped end which fits the vent-hole of the cap, and which 125 contains an escape-port, *o*², to allow the vapor to escape from the filled cans when heated, 130

the soldering being done by ejecting molten solder in the cap-crease from the molten-solder receptacle L, as when soldering the ends of cans, as before stated. The cans may be 5 capped, or the entire head soldered in, the latter being the most desirable, as the cans are more conveniently filled.

The machine having all its mechanism supported on the vertical shaft C, and suspended 10 from the hanger A, dispenses with a table or frame, thereby making all the adjustments readily accessible, simplifying the machine, and occupying less space.

Having described my invention, what I claim 15 as new, and wish to secure by Letters Patent, is—

1. In a can-soldering machine, the combination of the rotating vertical shaft C, the rotary table G, rotating thereon freely, mechanism to 20 impart to the table G an intermittent movement, and the hanger A, supporting the said intermittent mechanism, whereby an under-supporting table or frame is dispensed with.

2. The combination of the rotary vertical 25 shaft C, the table G, supported thereon and rotating intermittently around the rotating shaft C, and mechanism centrally supported that will move, stop, and hold the table G, whereby free access may be had to all parts of 30 the machine.

3. The combination of the central shaft, C, can-holder d, wheel E, the intermitting mechanism, and the rotary table G, placed between the intermitting mechanism and the wheel E, 35 whereby the table G is rotated from above, and the can-holders rotated from below the table.

4. The combination of the vertical shaft C, the crank c, the pendulum D, the pin or pawl 40 r', and rotary table G, provided with ratchet-teeth u, for the purpose as herein specified.

5. The combination of the rotary table G, swiveled can-holder d, external gear-wheel, F, internal gear-wheel, E, and pinion k, for 45 the purpose shown and described.

6. The combination of the vertical shaft C, rotary table G, hanger A, brake-shoe q², and stop-pin t, whereby the brake steadies the forward movement of the table G when the pin t is disengaged therefrom. 50

7. The combination of the rotary central shaft, C, can-holder d, wheel E, the intermittent mechanism, the rotary table G, placed between the intermittent mechanism and the wheel E, and a molten-solder-applying device, 55 whereby both ends of the can may be soldered at the same time, for the purpose and as herein specified.

8. The combination of the rotary table G, the swiveled or pivoted can-holder d, pinion 60 k, and means that will hold the pinion k in contact with either of the master gear-wheels E or F, for the purpose as set forth.

9. The combination of the rotary table G and a rotary can-holder provided with a rotating cylindrical ring, d, which protects the upper part of the can placed therein from the heat, for the purpose as specified. 65

10. The combination of a rotating cylindrical ring, d, and arms d', which will allow 70 a portion of the can-body to project below the ring d, for the purpose as herein described.

11. The combination, in a rotary can-holder, of the cylindrical rings d, arms d', and the protecting-plate d², for the purpose as set 75 forth.

12. The combination of the rotary table G, rotary can-holder d, the pinion k, internal gear-wheel, F, the cap-holding pin x, provided with the port o², and the molten-solder-applying device, for the purpose as herein specified. 80

In testimony whereof I affix my signature in presence of two witnesses.

DAVID M. MONROE.
